UNITED STATES PATENT OFFICE.

ETHAN I. DODDS, OF PITTSBURGH, PENNSYLVANIA, ASSIGNOR TO FLANNERY BOLT COMPANY, OF PITTSBURGH, PENNSYLVANIA.

ILLUMINATING MEANS.

1,385,778.

Specification of Letters Patent. Patented July 26, 1921.

Application filed July 25, 1917. Serial No. 182,744.

To all whom it may concern:

Be it known that I, ETHAN I. Dodds, a citizen of the United States, and a resident of Pittsburgh, in the county of Allegheny and State of Pennsylvania, have invented 5 certain new and useful Improvements in Illuminating Means; and I do hereby declare the following to be a full, clear, and exact description of the invention, such as 10 will enable others skilled in the art to which it appertains to make and use the same.

This invention relates to improvements in illuminating means and more particularly to lamps,—the object of the invention being to provide a simple and efficient lamp 15 which shall be so constructed as to provide a cold light and especially useful for providing a moderate illumination in a room, or a cabin or other part of a ship, such as 20 in a submarine.

A further object is to provide a lamp in which the light giving element is such as may be energized, activated, or caused to absorb light periodically by means of a source of 25 light caused to appear for limited lengths of time within the inclosure of the lamp, and to provide a portion of the light giving material with an element which will render the same permanently active and luminous 30 and also serve, to a more or less limited degree, to tend to energize the major portion of said material.

With these and other objects in view, the invention consists in certain novel features 35 of construction as hereinafter set forth and pointed out in the claims.

In the accompanying drawings; Figure 1 is a sectional view of a lamp embodying our 40 invention; Fig. 2 is a plan view; Figs. 3, 4 and 5 are views showing modifications.

1 represents a globe which may have a general spherical shape and formed at its top with a mouth portion 2 which may be received by any suitable lamp body or 45 bracket for supporting the globe 1 and its contents.

An inner globe 3 is disposed within the globe 1 and is made with a closed bottom 4 and an open mouth portion 5,—the latter 50 being supported by the mouth portion 2 of the outer globe and may be fused thereto so as to provide a chamber between the two globes which may be exhausted if desired.

Before the two globes are assembled, the 55 inner surface of the outer globe is coated

with a luminous material,—viz. a phosphorescent material which has the property of absorbing light and then emitting the light so absorbed. The material which may be employed for the major portion 6 of the 60 coating may comprise such material as zinc or calcium sulfid and preferably an infinitesimal amount of radioactive material, such as a salt of radium. A small portion 7 of the luminating material in the bottom 65 of the globe may comprise the same ingredients as those of the coating 6, but with a sufficiently greater proportion of radium salt to render the same permanently luminous and so that the rays or emanations from the 70 body or mass 7 of the coating will serve, not only to afford a permanently luminous spot on the globe, but also to a more or less limited degree to activate the main portion 6 of the coating.

A source of light such as an electric lamp 8 is located within the inner globe 3, and by lighting said lamp 8 at intervals and for limited periods of time, the coating of luminous material will be activated or energized and 80 the coating and consequently the globe will be caused to glow with a sufficient brilliancy to illuminate a surrounding area for ordinary purposes where a moderate, cold light is desirable.

Instead of applying a single mass of permanently luminous material 7 centrally in the bottom of the globe 1 as shown in Figs. 1 and 2, we may provide several masses or spots 9 of such material as shown in Figs. 90 3 and 4.

Instead of coating the interior of the outer globe with luminous material, such coating may be applied to the exterior of the inner globe 3, and the permanently luminous portion or mass of the coating will be located 95 in the bottom of the inner globe 3.

Having fully described my invention, what I claim as new and desire to secure by Letters Patent, is:—

1. Illuminating means comprising a globe having a coating therein of phosphorescent material, a portion of said coating consisting of phosphorescent material combined with radioactive material in sufficient quantity to render said portion of the coating permanently luminous.

2. Illuminating means comprising a globe, a coating therein of phosphorescent material, a separate portion of said coating hav-

ing radioactive material incorporated there-
in in sufficient quantity to render such por-
tion of the coating permanently luminous,
and a source of light within said globe for
5 activating or energizing said coating to en-
hance the luminosity thereof.

3. Illuminating means comprising two
globes one within the other, a source of light
within the inner globe, and one of said globes
10 having a coating of phosphorescent material,
a portion of said coating having radioactive
material incorporated therein in sufficient
quantity to render such portion of the coat-
ing permanently luminous.

15 4. Illuminating means comprising two

globes, one within the other, a source of light
within the inner globe, a coating of phos-
phorescent material on the inner surface of
the outer globe, and a portion of said coating
in the bottom of the outer globe containing
sufficient radioactive material incorporated
therein to render the same permanently
luminous.

20 In testimony whereof I have signed this
specification in the presence of two subscrib-
ing witnesses.

25 ETHAN I. DODDS.
